LAMINATED ABRASIVE WHEEL

Edward Hurst, West Newton, Mass., assignor to
United Cotton Products Company, Fall River,
Mass., a corporation of Massachusetts

Application March 31, 1945, Serial No. 585,860

7 Claims. (Cl. 51—193)

1

This invention relates to the manufacture of abrasive wheels. More particularly, it relates to abrasive wheels of the type consisting of a rotatable hub and a detachable annular rim, the latter being provided with an abrading or polishing surface. It also pertains to the method of making such wheels.

Abrasive wheels for polishing and other light abrasive finishing operations, commonly referred to in the trade as "set-up" wheels, have usually been made heretofore by applying a layer of animal glue or other adhesive to the peripheral surface of the supporting wheel body, and loading the glue coated surface with the desired abrasive substance. Since the resulting abrasive-coated periphery is rigid and inflexible it is customary to pound the periphery of the wheel with a blunt instrument to fracture the abrasive-glue coating. The grinding and polishing surfaces of wheels so made are at best lacking in uniformity, and harsh and irregular in their cutting action, since they depend almost entirely upon the background or body of the wheel for whatever resilience or softness they possess, and if sufficient adhesive and abrasive is applied to the surface to give the wheels any satisfactory degree of durability the resilience of the wheel body is so far removed from the grinding surface as to lose a greater part of its cushioning effect upon the work being surfaced. Moreover, set-up wheels of the prior art have an unsatisfactorily short life, requiring a renewal of the grinding surfaces after a use of only a few minutes, or a matter of a few hours at most, depending upon the operation being performed and the type and amount of abrasive coating on the wheel. The action of the wheel during its useful life varies from a reasonably acceptable performance by the freshly prepared surface to a point where the cutting action is so ineffective that the surface must be renewed. The application of glue and abrasive to the surface is furthermore a messy and unpleasant job and its elimination would be a distinct advantage for the latter reason alone.

It is an object of the present invention to provide an abrasive wheel for fine grinding and finishing operations which will be highly satisfactory in use and also will avoid the disadvantages set forth above. It is a further object to provide such a wheel which will have an exceptionally long life as compared with abrasive wheels heretofore employed for similar uses and which will provide satisfactory cutting action throughout its useful life. A still further object is the

provision of a wheel of the herein-described type in which the abrading member of the wheel can be facilely replaced after a satisfactory long and economical life. Further advantages of the present product include improved resilience and smooth operational qualities of the wheel throughout its useful life and an ability to retain its smooth, cool and free cutting nature by reason of its habit of self-dressing during grinding operations.

In accordance with the present invention an abrasive wheel for fine grinding and finishing is made with a rotatable hub member and a detachable annular rim member, the latter being provided with an annular side grinding or peripheral grinding surface of abrasive material. The wheel of the present invention is further characterized in that the abrasive material constituting the annular or peripheral grinding surface of the wheel is composed of a large number of individual abrading members suitably secured upon and engaged by the detachable annular rim and consisting of a fabric-reinforced felted fibrous abrasive-included sheet material. Other details and features of the present invention will become apparent as the description proceeds.

In order to more clearly understand the nature of the present invention, reference is made to the drawings in which:

Figure 1 is a plan view of one face of a fragmentary portion of a fabric-reinforced felted fibrous abrasive-included strip material employed in the process of forming the reinforced abrasive strip material embodied in the present invention;

Figure 2 is a like view of the opposite face of the strip material shown in Figure 1;

Figure 3 is an exaggerated vertical cross section through the line 3—3 in Figure 1;

Figure 4 is a plan view of the fabric-reinforced abrasive strip material of Figures 1, 2, and 3 after it has been doubled back upon itself with a metal bar strengthening element included in the base portion of the U-shaped strip material and die struck to mark off designated short lengths of the strip prior to cutting into abrasive segments;

Figure 5 is an exaggerated vertical cross-section through the line 5—5 in Figure 4;

Figure 6 is a plan view of one of the notched abrading elements obtained by cutting segments from the strip material of Figures 4 and 5;

Figure 7 is a plan view of a modified form of notched abrading element made according to the present invention;

Figure 8 is an exaggerated vertical cross-section through the line 8—8 in Figure 7;

Figure 9 is a fragmentary plan view of an abrasive wheel embodying the present invention and having a peripheral grinding surface composed of the abrasive elements shown in Figure 6;

Figure 10 is an expanded cross-section through the line 10-10 of Figure 9;

Figure 11 is a plan view of an abrasive wheel embodying the present invention and having an annular side grinding surface composed of the abrasive elements shown in Figure 6; and

Figure 12 is a section taken along the line 12-12 of Figure 11.

The abrasive character of the wheels of the present invention is imparted by the abrasive-included felted fibrous sheet material, such as for example, that described more fully in my Patents Nos. 2,284,738 and 2,284,739. Briefly, the abrasive sheet material defined in the aforesaid patents, and which I have found to be satisfactory for making the present wheels, is composed of a plurality of carded fibrous membranes which have been superimposed one on the other and the fibers intertwined to form when compacted a strong, substantially non-lamellar fibrous web. During the process of forming the fibrous web material abrasive grain of the desired particle size, and adhesive binder, are incorporated internally of the web to form a sheet material which is abrasive in character throughout its thickness. For further details of such abrasive sheet material and methods of making it, reference is made to my above-mentioned patents.

Referring further to the drawings, Figures 1, 2 and 3 are various views of a fragment of abrasive strip material such as is formed in the process of making the abrading elements constituting the grinding surface of wheels of the type herein described. A long strip of woven fabric 10 serves as a reinforcing base or core for the abrasive strip material to be formed, the weight of the fabric chosen being dependent upon the character and size of the abrasive particles embodied in the felted abrasive strip attached, the number of layers of abrasive material to be applied to the core and the particular use for which the wheel is being made. It is important for most satisfactory results that the warp threads 11 of the reinforcing fabric run lengthwise of the strip and the weft or filling threads 12 of the fabric run perpendicular thereto. As will be apparent as the description proceeds, such a disposition of the warp and weft threads will result in the warp threads being disposed parallel to the axis of rotation and the weft or filling threads will be disposed radially of the wheel. A woven fabric which has been found highly suitable is a cotton drill cloth having a thread count of 124 x 60, the warp thread count being given first.

A number of strips of abrasive included felted fibrous sheet material of different widths are then adhesively attached to both faces of the reinforced fabric core. As shown in Figures 1, 2, and 3, two narrow strips 13 and 14 are attached by means of adhesive 15 to one face of the fabric 10 with the outer edges even with and following the outer edges of the fabric so that the fabric has a clear area 16 centered laterally and extending lengthwise of the strip. On the other face of the fabric core 10, two broad strips 17 and 18 of the abrasive-containing felted fibrous material, which in total width are almost equal to the width of the fabric strip 10, are secured thereto by adhesive 15, after which narrower strips 19 and 20 are adhesively secured by adhe-

hesive 15 to the strips of abrasive-included fibrous material 17 and 18 previously adhered to the fabric strip 10. Casein has been found highly satisfactory as the adhesive for securing the various elements of the reinforced strip together.

Other adhesives which can be used include high grade animal glue, particularly when hardened with formaldehyde, and adhesives such as phenolic and urea resin adhesives and the like. All the strips of abrasive-included fibrous sheet material are co-extensive in length with the length of the fabric reinforcing strip.

After a composite strip of abrasive material such as that shown in Figures 1-3, inclusive has been formed, the strip is bent or folded back upon itself midway between its side edges and lengthwise of the strip so that the fabric and its adherent abrasive-included fibrous sheet material form a U-shaped element with an additional 15 coating of adhesive 15 holding the thusly pressed strip in that position. At the time of folding and pressing the strip material to U-shape a ribbon or bar 21 of metal or similar rigid material co-extensive in length with the strip of fabric 10 and approximately equal in thickness or gauge to the combined thickness of layers 13 and 14 attached to the inner sides of the fabric 10 and of a width approximately equal to one half the width of the clearance space 16 left on the side of the fabric shown in Figure 1 between abrasive strips 13 and 14 is inserted in the base of the U-shaped strip. The bar 21 serves to stiffen and strengthen the abrading elements to be cut from the strip material.

35 The abrasive strip is further subjected to pressure with special dies to mark such designated segments 22 separated by narrow grooves 23 and circular depressions 24 extending inwardly from the outer edge of the strip material to the bar or ribbon 21. The strip in its folded form as thus 40 stamped, as shown in Figures 4 and 5, is then separated along the grooves 23 and by severance of the metal bar adjacent the circular depressions to provide a number of individual abrading elements 25 such as that shown in Figure 6. Notches 26 are usually cut in each side of the unit 45 25 for engagement with the annular rim in making the abrasive wheel embodying those units. Each of the notches is so located that the lower 50 portion 27 cuts into the top edge of the metal ribbon 21.

Figures 7 and 8 depict by plan and vertical cross-sectional views, respectively, a modified form of segmental abrading element made similarly to the element shown in Figures 5 and 6 but differing in that the longer felted abrasive strips 17 and 18 of Figures 5 and 6 have been omitted and the lower edges of the shorter fibrous abrasive strips 13, 14, 19 and 20 do not extend downwardly all the way to the upper edge 60 of the rigid reinforcing element 21.

Figures 9 and 10 depict by fragmentary plan and expanded cross-sectional views, respectively, an abrasive wheel for finish grinding and polishing embodying the present invention, and in which the periphery of the wheel constitutes the grinding surface. In making such a wheel a plurality of individual abrading members 25 are assembled face to face on a metal support which is bent to form an annular rim 28, the sides 29 of the metal support being turned upwardly and the ends 30 thereof crimped or otherwise deflected inwardly so as to engage the notches 26 in the side of the abrasive members 25 to tightly and 70 firmly grip and hold the members in place. A 75

sufficient number of the abrading elements are contained in the channel shaped annular rim to fill the rim and provide a substantially continuous circumferential abrasive surface 31. It is to be observed that by the use of strips of felted fibrous abrasive material of different widths that each of the individual abrading members is somewhat tapered by successive stages from the base outwardly whereby the members when assembled to form a peripheral grinding surface tend to fit more closely together over their entire area. The annular rim containing the abrasive material is mounted upon a rotatable hub member comprising two side plates 32 having inwardly projecting hubs 33 constituting an integral part of said side plates. The plates 32 are provided with jaw portions 34 which between them fit about and securely hold the annular rim loaded with abrasive material in position. The hub portions 33 are adapted to be mounted on a suitable spindle 35 and held in place by nuts 36 and washers 37.

Figures 11 and 12 are plan and diametrical cross-sectional views of a modified form of abrasive wheel embodying the present invention and adapted for side grinding operation with an annular abrasive surface 38. The supporting annular rim 39, loaded with abrading units 25, which are engaged by the inwardly deflected sides 40 of the annular rim, is bent in such a way that the abrading elements when mounted project laterally from the wheel to provide an effective annular grinding face instead of the peripheral grinding face provided by the wheel of Figures 7 and 8. The abrading members 25 are preferably modified from the type shown in Figure 6 in that they are not provided with the same inward taper obtained by using abrasive strips of different widths but are substantially the same thickness from the top to the bottom by reason of having the outer layers 19 and 20 of abrasive-included material substantially co-extensive with layers 17 and 18. One or more wedge shaped pieces may be used, if desired, to provide for the slight difference between the inner and outer circumferences of the annular surface. The rim 39 loaded with abrasive material is rigidly and strongly secured to a rotatable hub member comprising a base plate 41 fastened to a suitable spindle 42 by bolts 43 and provided with an annular detachable flange 44 attached to the base plate 41 at the periphery by bolts 45 and having the upper edge 46 turned inwardly to engage the annular rim 39. The rim 39 is further secured by radially slideable curved engaging plates 47 which are bolted to the base plate 41 by means of bolts 48 and when fastened in position clamped tightly against the inner side of the rim to force it against the flange and hold the abrasive rim firmly in position.

It is highly desirable, and most satisfactory grinding action is obtained, when the warp threads of the reinforcing fabric core of the individual abrading members lie in a lengthwise direction substantially parallel to the operating abrasive surface of the wheel with the filling threads consequently lying substantially perpendicular to the abrading surface of the wheel. Such a disposition of the threads provides a means of continuously renewing the abrasive surface without requiring a separate dressing of the wheel. When a warp thread becomes exposed when parallel to the abrading surface it quickly and easily strips out exposing the soft ends of the low-twist filling threads. The filling threads are usually made from soft-twist yarns which untwist

or ravel very easily so that the filling thread ends wear away and again expose another warp thread, thereby repeating the self-dressing action.

If it is desired to renew or dress the abrading surface of the wheel to a greater extent than it is dressed during the normal operation of the wheel, such renewal or increased dressing action can be readily accomplished by removing the wheel from the shaft and replacing it on the shaft with the side faces in reversed positions. As reversed, the edges of the individual abrasive segments, which were previously leading edges as the segments made contact with the work being surfaced, become the trailing edges and the abrading surface of each segment is given an augmented dressing action over and above that which it receives during continual operation of the wheel. However, the disposition of the threads is such that it is not essential that the wheel be reversed under ordinary usage.

The filling threads never extend excessively beyond the abrasive surface in such a way as to mask the cutting action of the abrasive due to the tendency of the wheel in action to pinch any extending fibers between the abrasive particles of the grinding surface and the work being ground and sever them. Consequently there is provided in abrasive wheels so made a fabric reinforcing core which serves to materially strengthen the resulting abrasive wheel and preserve the ability of the wheel to stand up to the work being surfaced without undergoing a ragged, excessive or premature destruction of the surface. At the same time the cutting action of the abrasive particles is in no way interfered with by the presence at the surface of an excessive amount of non-abrasive material.

Another advantageous feature of the presently constructed wheels is the added opportunity which such a construction affords to obtain resiliency in abrasive action with an exceedingly wide range of grade hardness of the abrasive material constituting the abrasive element of such wheels. It is evident from a consideration of the abrasive device of the multiple segment type construction herein disclosed that the individual segments making up the abrasive surface are each free to move relative to each other as contact with the work is made so that an appreciable amount of motion and resilience is obtained over that ordinarily obtained as a result of the material resiliency inherent in the abrasive included felted fibrous sheet material itself embodied in the wheel. The density, and consequently the hardness grade, of each abrasive segment can be increased or decreased by raising or lowering the amount of pressure employed in compacting the fibrous abrasive-containing material onto the fabric reinforcing core.

Having described and set forth the invention in detail it is desired to claim:

1. An abrasive wheel comprising a rotatable hub member and a detachable annular member attached thereto, said annular member comprising a channel shaped annular rim having at least a part of the sides deflected inwardly and a plurality of abrasive members positioned in and circumferentially filling said channel shaped rim, each of said abrasive members comprising several layers of abrasive-included felted fibrous sheet material adhesively secured to a woven fabric reinforcing element each of said abrasive elements being strengthened by an internally secured rigid bar member extending transversely across the base portion of said abrasive element,

said abrasive elements having lateral recessed portions engaged by the inwardly deflected portions of the sides of said annular rim.

2. An abrasive wheel comprising a rotatable hub member and a detachable annular member attached thereto, said annular member comprising a channel shaped annular rim having at least a part of the sides deflected inwardly and a plurality of slab-shaped abrasive members disposed parallel to the axis of said rotating hub member and extending radially from and circumferentially filling said annular rim to constitute a peripheral abrading surface, each of said abrasive members comprising several layers of abrasive-included felted fibrous sheet material adhesively secured to a woven fabric reinforcing element, each of said abrasive elements being strengthened by an internally secured rigid bar member extending transversely across the base portion of said abrasive element, said abrasive elements having lateral recessed portions engaged by the inwardly deflected portions of the sides of said annular rim.

3. An abrasive wheel comprising a rotatable hub member and a detachable annular member attached thereto, said annular member comprising a channel shaped annular rim having at least a part of the sides deflected inwardly and a plurality of slab-shaped abrasive members disposed parallel to the axis of said rotating hub member and radially disposed in sufficient number to circumferentially fill said channel shaped annular rim and projecting laterally therefrom to provide an annular abrading surface, each of said abrasive members comprising several layers of abrasive-included felted fibrous sheet material adhesively secured to a woven fabric reinforcing element, each of said abrasive elements being strengthened by an internally secured rigid bar member extending transversely across the base portion of said abrasive element, said abrasive elements having lateral recessed portions engaged by the inwardly deflected portions of the sides of said annular rim.

4. An abrasive wheel comprising a rotatable hub member and a detachable annular member attached thereto, said annular member comprising a channel shaped annular rim having at least a part of the sides deflected inwardly and a plurality of slab-shaped abrasive members positioned in and circumferentially filling said annular rim, each of said abrasive members comprising a U-shaped woven fabric reinforcing element having a plurality of layers of abrasive-included felted fibrous sheet material adhesively secured to the sides of the woven fabric reinforcing element and stiffened by a transversely disposed rigid bar element secured within and at the base of said U-shaped fabric reinforcing element, said abrasive members having lateral recesses engaged by the inwardly deflected sides of said annular rim.

5. An abrasive wheel comprising a rotatable hub member and a detachable annular member attached thereto, said annular member comprising a channel shaped annular rim having at least a part of the sides deflected inwardly and a plurality of slab-shaped abrasive members positioned in and circumferentially filling said annular rim, each of said abrasive members comprising a U-shaped woven fabric reinforcing element having a plurality of layers of abrasive-

included felted fibrous sheet material of different widths adhesively secured to the sides of the woven fabric reinforcing element and extending inwardly from the upper edge thereof, each of said abrasive members being stiffened by a transversely disposed rigid bar element secured within and at the base of said U-shaped fabric reinforcing element, said abrasive members having lateral recesses engaged by the inwardly deflected sides of said annular rim.

6. An abrasive wheel comprising a rotatable hub member and a detachable annular member attached thereto, said annular member comprising a channel shaped annular rim having at least a part of the sides deflected inwardly and a plurality of slab-shaped abrasive members positioned transversely in and circumferentially filling said annular rim, each of said abrasive members comprising a U-shaped woven reinforcing element so disposed that the warp threads thereof lie parallel to the axis of rotation of said wheel and the weft or filling threads thereof lie radially of the wheel, a plurality of layers of abrasive-included, felted fibrous sheet material adhesively secured to the faces of the woven fabric reinforcing element and extending inwardly from the peripheral edge of said reinforcing element over the greater part of said fabric reinforcing element, and a rigid strengthening element secured within and at the base of said U-shaped fabric, said abrasive member having lateral recesses engaged by the inwardly deflected sides of said annular rim.

7. An abrasive wheel comprising a rotatable hub member and a detachable annular member attached thereto, said annular member comprising a channel shaped annular rim having at least a part of the sides deflected inwardly and a plurality of abrasive members positioned in and circumferentially filling said channel shaped rim, each of said abrasive members comprising several layers of abrasive-included felted fibrous sheet material adhesively secured to a woven fabric reinforcing element, said woven fabric reinforcing element being so disposed that the warp threads thereof lie parallel to the axis of rotation of said wheel and the weft or filling threads thereof lie radially of the wheel, each of said abrasive members being strengthened by an internally secured rigid bar member extending transversely across the base portion of said abrasive element, said abrasive members having lateral recessed portions engaged by the inwardly deflected portions of the sides of said annular rim.
